His ATTORNEY.

UNITED STATES PATENT OFFICE.

WILLIAM L. PATTISON, OF KANSAS CITY, MISSOURI.

GRATING.

Application filed December 17, 1926. Serial No. 155,396.

My invention relates to improvements in gratings, such as are commonly used for flooring.

It relates particularly to the type of gratings having longitudinal bars disposed edge up and tied together by cross braces.

One of the objects of my invention is to provide a novel grating of the kind described having novel means for bracing the longitudinal bars, which is simple, cheap and easy to make and assemble, which is strong, light, durable and not liable to break or become distorted with use, and which affords a maximum of space for the transmission of light therethrough.

The novel features of my invention are hereinafter fully described and claimed.

In the accompanying drawing, which illustrates the preferred embodiment of my invention,

Fig. 1 is a plan view of my improved grating.

Fig. 2 is a section on the line 2—2 of Fig. 1.

Fig. 3 is a cross section on the line 3—3 of Fig. 1.

Fig. 4 is a perspective view of one of the brace members.

Similar reference characters designate similar parts in the different views.

The grating is provided with longitudinal bars 1, disposed edge up, preferably parallel with each other.

Between each pair of adjacent bars 1 are disposed a plurality of angle brace members, the end portions 2 and 3 of which are at right angles to and extend horizontally in opposite directions from a transverse portion 4, after the manner of commercial Z angles used in steel structural work.

The brace members between each pair of bars 1 have their end portions 2 and 3 each provided with a transverse hole 5, Fig. 4, adapted to register with a transverse hole 45 in the adjacent bar 1 and to receive therethrough a rivet 6, which also extends through the end portion of an adjacent brace member at the opposite side of the bar. Adjacent brace members between the different pair of bars 1 have their transverse portions 4 aligning with each other, as shown in Fig. 1, the brace members being disposed so that the rivets 6 connect like end portions of adjacent brace members, that is, the end portions 2 with the end portions 2 and the

end portions 3 with the end portions 3 of adjacent brace members.

By having the transverse portions 4 of adjacent brace members aligned with each other, a rigid structure is effected, and by having the rivets 6 which fasten the end portions 2 out of alignment with the rivets 6 which fasten together the end portions 3, and opposite sides of the transverse portions 4, great resistance to the brace members 65 swinging on their fastening rivets is afforded.

By having the brace members between each pair of bars 1 independent of each other, they may be very quickly assembled 70 and riveted, as the fastening of one brace member does not position the adjacent brace members between said pair of bars.

By means of the construction described a maximum of light space is afforded for the 75 transmission of light through the grating, while affording a maximum of strength, and a structure which is relatively light and inexpensive for material and transportation charges, and economical to manufacture. 80

I do not limit my invention to the structure shown and described, as modifications, within the scope of the appended claims, may be made without departing from the 85 spirit of my invention.

What I claim is:

1. A grating of the kind described comprising longitudinal bars, and brace members independent of each other disposed between the bars of each pair of said longitudinal bars, each brace member having a transverse portion aligning with the transverse portions of adjacent brace members located between the other pairs of bars, each brace member having its end portions at 90 right angles to and extending in opposite directions from its transverse portion, said end portions of said brace members being respectively fastened to the adjacent bars, and like end portions of adjacent brace members being fastened together and to the opposite sides of the bars to which they are fastened.

2. A grating of the kind described comprising longitudinal bars each having a longitudinal row of transverse holes, brace members disposed between the bars of each pair of said bars and independent of each other, each brace member having a transverse portion aligning with the transverse portions 105 110

of adjacent brace members which are located between the other pairs of said bars, each brace member having its end portions at right angles to and extending in opposite directions from its transverse portion, each end portion having a transverse hole, like end portions of adjacent brace members being disposed at opposite sides of the bars

against which they bear, and rivets extending through the holes in said end portions and the adjacent bars and fastening like end portions to each other and to the adjacent bars.

In testimony whereof I have signed my name to this specification.

WILLIAM L. PATTISON.
